EDWARD E. HENDERSON, OF NEW YORK, N. Y., ASSIGNOR TO NIPS PATENT CORPORATION, OF NEW YORK, N. Y., A CORPORATION OF NEW YORK

APPARATUS FOR PRODUCING LIQUID PACKAGES

Application filed January 13, 1928, Serial No. 246,457. Renewed November 3, 1931.

My invention relates to apparatus for producing liquid packages, each consisting of a glass container filled with a liquid and sealed.

While the apparatus in certain of its characteristics or aspects is adapted or adaptable to the production of packages having substantially varying character, it is especially well adapted for the manufacture on an economical and high production basis, of filled perfume containers of the character disclosed in U. S. patents to Walter Goodchild, No. 1,397,631, dated November 22, 1921; No. 1,452,801, dated February 25, 1921; and No. 1,517,780, dated December 2, 1924. The invention will, therefore, be particularly described as adapted for the production of such packages or filled containers, with the understanding that in the broader aspects of the invention I do not limit myself to utilization of the mechanism for production of the specific article described or to the filling of glass containers with perfume, since evidently the process and apparatus are adapted or adaptable to substantial variations in the container itself or in the character of liquid with which it is filled.

The above identified patents fully explain the advantage of packaging and sealing a regulated quantity of a liquid, and especially a very small quantity of a valuable liquid such as a perfume of high quality, and reference is hereby made to them for an understanding of such advantages.

In addition to disclosing a package or filled container having characteristics similar to those produced by the present apparatus, the above identified patents disclose one relatively crude filling method and relatively primitive or rudimentary apparatus by which the stated packages may be produced, by what amount to "hand" methods of manufacture; and while such methods and apparatus are practical and operative, they are relatively slow and uneconomical, and do not permit the packages to be produced at practically low cost, or with reasonable margin of profit when sold at a moderate cost to the consumer.

The general purpose of the present invention is to provide improved and practical automatic sealing mechanism by which the filled

containers may be turned out in large volume at low cost.

The characteristics and advantages of the invention are further sufficiently explained in connection with the following detail description of the accompanying drawings, which illustrate one exemplifying embodiment of the apparatus. After considering this example, skilled persons will understand that many variations may be made and I contemplate the employment of any structures which are properly within the scope of the appended claims.

Fig. 1 is a longitudinal section of one of the glass containers, the size of the container being considerably exaggerated for clearness of illustration.

Fig. 2 is a perspective view of parts of the apparatus, explaining steps of the process.

Fig. 3 is a section of apparatus to explain the filling operation.

Fig. 4 shows the container after sealing at one end and filling.

Fig. 5 explains the preheating operation and also shows one of the cooling means or devices.

Fig. 6 explains sealing and cooling operations.

Fig. 7 shows the completed container.

Fig. 8 is a plan view of apparatus embodying the invention in one form.

Fig. 9 is a vertical section at 9—9, Fig. 8.

Fig. 10 is a view, principally in elevation from the left of Fig. 8, with certain parts in section.

Fig. 11 is a detail view of an adjusting device.

Fig. 1 shows a glass container which I may call for convenience, a flask, ready for the filling and sealing operations, and which is produced in a manner disclosed in Patents No. 1,397,631 and No. 1,452,801, above referred to. For the purpose of packaging such liquids as expensive perfumes, a relatively minute quantity is desirably inclosed and preserved in each flask. The flask F is actually much smaller than is shown in Fig. 1, but has substantially the same relative proportions. The glass used for the flasks is desirably of a suitable quality of lead glass, the

fracture of which produces relatively blunt or non-sharp edges.

The central or body portion 1 is of substantially larger diameter than the ends 2, and holds by far the greater part of the liquid. The ends are of small diameter, and the passages 3 through them are of capillary size. The ends are connected to the body by generally tapering formations 4. In carrying out the present improved filling and sealing process, made possible by the improved machine, in distinction from the old process as disclosed in the above identified patents, and in which the containers or flasks are first filled and then the ends successively sealed, one end of each empty flask is first sealed by inserting the tip of such end in a suitable flame to fuse the glass and form it into a solid or impervious closure ball or globule 5, Fig. 4. Fig. 2 shows one approved way of sealing one end of each of a continuous series of the flasks, comprising arranging the flasks in successive pockets 6 of a continuous conveyor 7, the ends to be sealed being positioned in line or in a plane, and the conveyor then moving these ends successively in contact with flame jets 8, by which the glass is melted and the ball end 5 is formed. No especial precaution, such as cooling by blasts of air, is necessary in this operation, since the sealing ball forms itself properly upon subjection to properly arranged flames in the absence of any liquid in the flask; but I have found that it is practically essential for rapid and perfect sealing in the operation now described and more especially in the second sealing operation as described later, to provide a very hot and efficient flame; and for this purpose the flames 8 are produced by the combustion of ordinary illuminating or heating gas combined with oxygen in suitable proportions, the burner and gas supply means being later described in detail.

The flasks, sealed at one end as described, are then collected and any suitable number of them are placed, as shown in Fig. 3, with their unsealed ends downward and immersed in a desired liquid to be packaged, such as perfume P, in a vessel V, which is located in a vacuum jar J having a sealing cover J¹. Air is then exhausted from the vacuum jar, thus causing the exhaustion of air from the flasks, the air thus extracted bubbling from their open ends and up through the perfume. When the desired degree of exhaustion has been obtained, air is admitted to the jar up to normal atmospheric pressure, and this pressure is exerted upon the surface of the liquid P, which is forced into the open ends of the flasks, which are thus practically perfectly filled with the liquid. Owing to the small diameter of the flask bodies, and especially the capillary diameter of the open end, liquid does not escape in any reasonable time interval or with any necessary handling of

the flask after filling and until the remaining open end is sealed.

The filled flasks are collected in suitable quantity and supplied to the pockets 8 of a continuous conveyor 9 and the unsealed end portions of the flasks are thus carried in contact with a flame 10 issuing from a preheating burner 11. By this preliminary heating a small amount of the liquid is driven out of the open flask ends in order to prevent interference by the liquid in such ends with the sealing operation. Suitable precaution is now taken to prevent overheating or improper heating, which would result in discharge of an excessive amount of the liquid or interference by such liquid with the sealing operation, such precaution, consisting principally in cooling the flask ends and other portions by air blasts. Thus, subsequent to the preheating operation an air blast is directed upon the ends of the flasks from a jet or nozzle 12. The flask ends are then passed in contact with flames 14 which are supplied by a suitable mixture of heating or illuminating gas and oxygen, and the fine glass ends are thus melted and the second end closure is produced in the form of an impervious sealing ball or globule 15, Fig. 7. Various portions of the flasks are also desirably cooled during and after sealing; thus an air blast is applied to the end portions 2 at points adjacent their tapered formations 4 as at 16, Fig. 6, and also to central portions of the flasks by blasts indicated at 17, these cooling effects being produced preferably throughout the travel of the flask ends through the sealing flames and also throughout a substantial course of travel before and after the sealing operation, thus keeping the flask as a whole at low temperature and tending to keep the liquid therein retracted and away from the vicinity of the sealing flame. Another cooling blast from a jet or nozzle 18 is also desirably applied to the sealed ends just after completion of the sealing operation. This arrangement or control of the cooling effects prevents interference with the proper sealing operation by the liquid contents of the flask, and permits the sealing flames 14 to properly melt the fine end portions 2 and form the solid and impervious second seal or closure 15.

The completed, filled container or package as shown in Fig. 7 is practically completely filled with perfume, only a minute part of the total flask content having been lost in the heating operations.

The completed flasks are collected and packaged in any desired way for shipment and sale.

Further details or refinements in the process will be understood after description of the mechanism, which is practically automatic in its operation and which is designed to carry out the process as described above

automatically and in an efficient, rapid and economical manner.

The machine as shown in Figs. 8 to 11 is arranged on a suitable base 20 which is placed 5 on a table at a convenient height for supervision by an attendant. While the machine is preferably arranged practically as an operative unit, and is so shown, it consists in a sense of two principal sections or groups, 10 the part A, Fig. 8, being designed for the first sealing operation, and the part B, for the second sealing operation.

Each principal section of the machine includes a conveyor; thus the part A has the 15 conveyor 7, and the part B, Fig. 10, has the conveyor 9, referred to in the process description. Each of these conveyors desirably consists of two pocketed wheels 21 and specifically these may be gear wheels of proper 20 tooth form or size to provide pockets in which the central portions of the flasks properly fit. The conveyor wheels of section A are secured in spaced relation on a shaft 23 and the wheels of section B are similarly 25 mounted on a shaft 24, these shafts being coaxial and also aligned with a central shaft 25, these shafts all being suitably mounted in bearings at the upper ends of brackets or columns 26, 27, 28, 29, 30 and 31. The central shaft 25 is conveniently driven at suitable speed by an electric motor 32 mounted 30 on the base and connected through worm gearing 33 and a pinion 34 with a gear 35 on shaft 25. On the ends of shaft 25 are 35 clutch members 36 to co-operate with movable clutch members 37 and 38 on the respective shafts 23 and 24. Each of the machine sections is provided with a clutch-shifting lever 39, conveniently located, whereby either or 40 both of the machine sections may be operated or stopped at will.

Each machine section also includes a downwardly inclined feed hopper 40, laterally dimensioned to receive any convenient number 45 of the containers in a position parallel to the shaft axis. A guide or guard in the form of a flexible or resilient strip of sheet metal 41 is anchored to the side walls of the feed hopper by a small rod 42 and has an angular 50 entrance formation 43. The guard extends about the conveyor wheels, slightly overlapping the inward ends of the teeth or pockets on each wheel, to a discharge point 44 where the flasks are discharged into a receiving tray 55 or hopper 45 which preferably slopes downward, rearwardly. The ends of the guide bands are curved outward at their discharge ends 46, and these ends are retained in proper position by pins 47 passing through the side 60 walls of the discharge tray. The inward ends of the feed hoppers and discharge trays are cut away or slotted to properly embrace the peripheries of the conveyor wheels, as indicated at 48 and 49.

65 Each machine section also includes a vertical

guide plate 50 to co-operate with ends of the flasks carried by the corresponding conveyor and properly position or direct the flasks in the respective sealing operation. These guide plates are supported at their ends by screw rods 51 passing through arms 53 on certain of the bearing brackets, namely, 70 27 and 30. The screw rods are positioned for the proper adjustment of the guide plates by nuts 52 revolvably mounted and secured 75 against axial movement in bearings 53a on arms 53.

Each machine section also includes a main burner comprising a hollow burner head 55 provided on its upper, arcuate face with a row of flame apertures or nozzles 56. The burner head is supplied with mixed gases through a hollow stem 57 which is pivotally mounted with suitable packing means 58 in the upper end of a burner body or mixer 59. As previously stated the best available flame for sealing is supplied by a suitable mixture of heating or illuminating gas and oxygen. Each burner therefore has a needle valve 60 controlling the flow of oxygen to a union 61 and another needle valve 62 controlling flow of gas through a pipe 63 to the same union, the latter being connected to the lower end of the burner body or mixer 59. Oxygen is supplied to the needle valve 60 through a pipe 64 leading from the usual adjusting or reducing valve 65 of an oxygen flask 66, which is also provided with a pressure gauge 67. The burner head when necessary is provided with additional air through an opening or pipe 68, and this auxiliary air flow may be induced by the flame draft, or in some cases might be supplied under pressure from an air supply source which provides air for cooling and other purposes as later referred to.

Machine section B for the second sealing operation includes in addition to the stated parts which are included in both sections, the following:

The pre-heating burner 11 referred to in the process description is located for contact with its flame of the flask ends 2 at a convenient point after the flasks have been picked up by the conveyor wheels. This heating of the flask ends volatilizes and drives out a small portion of the liquid. It has been found essential to carefully regulate the flame itself, and also its position in relation to the flask ends as they pass in contact with it. For these purposes, the burner proper is mounted on the upper end of a pipe 70 of flexible or bendable material such, for example, as brass, and in a simple arrangement, the adjustment of the flame position may be made by merely bending the pipe which will remain in the adjusted position. However, preferably, as shown, more definite mechanical means is provided for making and maintaining this adjustment, comprising a lever 71 embracing pipe 70 at 72 and pivotally mounted on a 110 115 120 125 130

bracket 73. In order to obtain universal adjustment of the burner, the lever is preferably slotted as at 74, and a bolt 75 passes through the slot and the bracket so that when the bolt is loosened, the pipe and the burner carried thereby may be adjusted in any direction as indicated by arrows in Fig. 11, and this adjustment may then be maintained by tightening the bolt. Since the degree of heat required for the preheating operation is generally not so great as is required for sealing, it is usually unnecessary to supply the preheating burner with oxygen. I have found that a suitable preheating flame is provided by a proper mixture of ordinary illuminating or heating gas and air. The preheating burner is therefore supplied with gas through a pipe 76 leading from a union 77. The needle valve 78 regulates the amount of gas supplied to pipe 70 through a union 79. Air may in some cases be supplied to the burner by induced draft, but preferably it is supplied under pressure from an air tank or accumulator 80 through a pipe 81 under control of a needle valve 82 to the union 79. By adjustment of the needle valve, the proportion of gases may be accurately regulated and the size of the flame may also be accurately adjusted to properly preheat the flask ends and drive out the proper amount of liquid.

The flask ends are desirably cooled adjacent the point of preheating, or specifically, as shown, just after preheating, by a jet of air issuing from the nozzle 12 previously mentioned in the process description. This nozzle is at the end of a pipe 85 leading from tank 80, and the position of the nozzle and of the zone of application of the cooling blast to the flask tips may be regulated by bending the pipe. The flasks are also desirably cooled throughout a substantial arc of their travel on the conveyor wheels by jets of air issuing from apertures or nozzles 86 in a curved pipe 87 underlying the flasks and located in the plane of the space between the two conveyor wheels as best shown in Fig. 8. The range or zone of cooling by these jets may extend, as shown in Fig. 10, from a point just posterior to the preheating point to a point posterior to the main heating or sealing burner 55. This cooling means provides for cooling the central portions of the flasks and the main body of the liquid content.

It is also desirable to additionally cool the flask ends, and for this purpose an arcuate pipe 88 is arranged practically parallel to the arcuate portion of pipe 87 but outside the left-hand conveyor wheel as shown in Fig. 8, and this pipe has air nozzles 89 for delivering jets of air against end portions of the flasks near their junctures with the central or body portions, throughout a range of travel similar to the range covered by the cooling nozzles 86. The last-named cooling means cools the liquid in the small ends of the

flasks close to the portions thereof which are heated and melted by the sealing flames, and together with the other cooling means practically holds back the liquid contents and prevents escape thereof during sealing, and even more important, prevents interference by the liquid with proper sealing.

Means is also desirably provided for properly controlling the direction of the sealing flames 8, this means being additional to the control of the positions of the flames by adjustment of the burner head. Conveniently, the stated flame control is obtained by an arcuate pipe 90 practically parallel to the pipe portions 87 and 88, but located outside the main burner. Pipe portion 90 has air jets or nozzles 91 directed upwardly. By properly positioning pipe portion 90, by bending or otherwise, the air jets issuing from its nozzles and passing upward adjacent the sealing flames 8, serve to divert such flames somewhat outwardly or to the left as viewed in Fig. 8, or in other words, prevents the flames from tending inwardly too close to the inward ends of the flask tips or adjacent the flask bodies, where such flame contact would tend to heat a larger mass of the liquid content. Additional cooling may also be provided for the formed ball seals 15 just after they leave the sealing flames, by a jet of air issuing from the end of a pipe 92, which may be arranged as a branch of pipe 85.

All of the pipes 85, 86, 88 and 90 may be connected by vertical portions to the tank or accumulator 80, which is supplied with air at suitable pressure from any suitable source such as a blower (not shown). Desirably, the air pipe leading from the blower is divided and enters the accumulator at two opposite points 93 and 94, to secure substantial uniformity of pressure of air supplied to all of the pipes leading from the accumulator. The blower or other air pressure device may in some cases be driven by motor 32, but otherwise the blower drive may be independent and the pressure may be maintained substantially constant by any known or suitable pressure regulator.

The main burner heads 55 may be pivotally adjusted to regulate the general angle of their row of air nozzles. Thus, as shown for each section of the machine, the main burner head is adjusted to cause the first sealing flame to strike the flask end portion some distance inward from the end thereof, and the other successive flames strike the flask tips at progressively outward points, until finally the formation of the sealing ball is completed by the action of the last flame. The guide plates 50 are also adjusted to properly direct the flasks in their longitudinal directions as they move past the sealing flames, this adjustment or positioning of the flasks depending somewhat upon the adjust-

ment of the respective sealing burner. One suitable relative adjustment of the burner and guide plate is shown for each section of the machine in Fig. 8.

8 The needle valves 60 and 62 for each sealing burner are properly regulated to secure the proper proportions of the gas and oxygen and also the proper size of sealing flames.

10 For either sealing operation any reasonable number of flasks are placed in the appropriate feed hopper 40, and are taken from the lower end of the hopper by the conveyor wheels and are properly retained in the pockets by the guide band 41 to the point of discharge into the receiving trough 45. The sealing operation performed in machine section A during the stated movement of the flasks, and the preheating, cooling and sealing operations performed in machine section 15 B, are sufficiently understood from preceding 20 description of the process and machine.

I claim:

1. A sealing mechanism for purposes described, comprising a continuous conveyor 25 having spaced pockets adapted to receive containers of the characters described, means for maintaining a series of sealing flame jets in the path of movement of the exposed container ends whereby to produce sealing formations thereon, and means for cooling portions of the containers adjacent the zone of 30 heating.

2. A sealing mechanism for purposes described, comprising a continuous conveyor 35 having spaced pockets adapted to receive containers of the character described, a sealing burner adjacent the path of movement of the exposed container ends, means for supplying a mixture of gases to the burner, a burner 40 providing a preheating flame anterior to said sealing burner, and means for cooling portions of the container ends adjacent the zone of preheating.

3. A sealing mechanism for purposes 45 described, comprising a continuous conveyor having spaced pockets adapted to receive containers of the character described, a sealing burner adjacent the path of movement of the exposed container ends, means for supplying 50 a mixture of gases to the burner, a burner providing a preheating flame anterior to said sealing burner, and means for cooling portions of the containers adjacent the zone of preheating and substantially throughout 55 the zone of contact with the sealing flames.

4. A sealing mechanism for purposes 60 described comprising a continuous conveyor having spaced pockets adapted to receive containers of the character described, said conveyor circulating in a substantially vertical plane, a feed hopper adapted to receive and position a plurality of containers and supply them to the successive conveyor pockets, receiving means into which the containers 65 are discharged from the conveyor, a sealing 70 burner adjacent one side of the conveyor providing sealing flame through which similar exposed ends of the successive containers pass, whereby impervious sealing balls are formed upon said ends, a preheating burner 75 adjacent the conveyor and anterior to the sealing burner for driving out a small part of liquid in the containers previous to the sealing operation and means for cooling the containers adjacent the locations of preheating and sealing.

5. A sealing mechanism for purposes described comprising a continuous conveyor having spaced pockets adapted to receive containers of the character described, said conveyor circulating in a substantially vertical plane, a feed hopper adapted to receive and position a plurality of containers and supply them to the successive conveyor pockets, receiving means into which the containers are discharged from the conveyor, a sealing burner adjacent one side of the conveyor providing sealing flame through which similar exposed ends of the successive containers pass, whereby impervious sealing balls are formed upon said ends, and means for cooling portions of the containers adjacent the zone of heating.

6. A sealing mechanism for purposes described comprising a continuous conveyor having spaced pockets adapted to receive containers of the character described, said conveyor circulating in a substantially vertical plane, a feed hopper adapted to receive and position a plurality of containers and supply them to the successive conveyor pockets, receiving means into which the containers are discharged from the conveyor, a sealing burner adjacent one side of the conveyor providing sealing flame through which similar exposed ends of the successive containers pass, whereby impervious sealing balls are formed upon said ends, and means for cooling portions of the containers adjacent the zone of heating.

7. A sealing mechanism for purposes described comprising a continuous conveyor having spaced pockets adapted to receive containers of the character described, said conveyor circulating in a substantially vertical plane, a feed hopper adapted to receive and position a plurality of containers and supply them to the successive conveyor pockets, receiving means into which the containers are discharged from the conveyor, a sealing burner adjacent one side of the conveyor providing sealing flame through which similar exposed ends of the successive containers pass, whereby impervious sealing balls are formed upon said ends, and a preheating burner adjacent the conveyor and anterior to the sealing burner for driving out a small part of liquid in the containers previous to the sealing operation, and means for applying a flow of cooling air to portions of the containers adjacent the zone of preheating.

8. A sealing mechanism for purposes described comprising a continuous conveyor having spaced pockets adapted to receive containers of the character described, said conveyor circulating in a substantially vertical plane, a feed hopper adapted to receive and position a plurality of containers and supply them to the successive conveyor pockets, receiving means into which the containers are discharged from the conveyor, a sealing burner adjacent one side of the conveyor providing sealing flame through which similar exposed ends of the successive containers pass, whereby impervious sealing balls are formed upon said ends, and means for supplying a flow of cooling air in con-

tact with portions of the containers throughout a large part of the zone of travel between the feed hopper and the receiving means.

8. A sealing mechanism for purposes described comprising a continuous conveyor having spaced pockets adapted to receive containers of the character described, said conveyor circulating in a substantially vertical plane, a feed hopper adapted to receive and 10 position a plurality of containers and supply them to the successive conveyor pockets, receiving means into which the containers are discharged from the conveyor, and a sealing burner adjacent one side of the conveyor 15 providing sealing flame through which similar exposed ends of the successive containers pass, whereby impervious sealing balls are formed upon said ends, said sealing burner being adjustable in relation to the conveyor 20 to adjustably position the sealing flame with reference to the passing containers.

9. A sealing mechanism for purposes described comprising a continuous conveyor having spaced pockets adapted to receive 25 containers of the character described, said conveyor circulating in a substantially vertical plane, a feed hopper adapted to receive and position a plurality of containers and supply them to the successive conveyor 30 pockets, receiving means into which the containers are discharged from the conveyor, a sealing burner adjacent one side of the conveyor providing sealing flame through which similar exposed ends of the successive containers pass, whereby impervious sealing 35 balls are formed upon said ends, a guide plate arranged for contact with ends of the successive containers opposite the ends to be sealed, for directing the containers in relation 40 to the heating flame, the guide being diagonally arranged to progressively advance the containers endwise.

10. A sealing mechanism for purposes described, comprising a continuous conveyor 45 having spaced pockets adapted to receive containers of the character described, said conveyor circulating in a substantially vertical plane, a feed hopper adapted to receive and position a plurality of containers and supply them to the successive conveyor pockets, receiving means into which the containers are discharged from the conveyor, a sealing burner adjacent one side of the conveyor 50 providing sealing flame through which similar exposed ends of the successive containers pass, whereby impervious sealing balls are formed upon said ends, a preheating burner adjacent the conveyor and anterior to the sealing burner for driving out a small part 55 of liquid in the containers previous to the sealing operation, and means for adjustably positioning the preheating burner.

11. A sealing mechanism for purposes described, comprising spaced conveyor wheels 60 simultaneously driven and provided with

spaced and aligned pockets to receive body portions of containers of the character described with reduced end portions of the successive conveyors projecting beyond the vertical face of one of the conveyor wheels, and a sealing burner positioned at the stated face of the conveyor wheel and provided with apertures for maintaining a series of diagonally arranged sealing flames in contact with the passing container ends.

12. A sealing mechanism for purposes described, comprising spaced conveyor wheels simultaneously driven and provided with spaced and aligned pockets to receive body portions of containers of the character described with reduced end portions of the successive conveyors projecting beyond the vertical face of one of the conveyor wheels, and a sealing burner positioned at the stated face of the conveyor wheel and provided with apertures for maintaining a series of sealing flames in contact with the passing container ends, and a cooling pipe located between the conveyor wheels and inward of the pockets and provided with a series of apertures for applying air jets to the central portions of the passing containers.

13. A sealing mechanism for purposes described, comprising two sealing sections each including a continuous conveyor having spaced pockets to receive containers of the character described, a drive shaft for the conveyor, a container feed hopper and means for receiving containers from the conveyor, and a sealing burner adjacent the conveyor for maintaining flame in contact with exposed end portions of the successive containers to form impervious sealing balls thereon, driving means operatively intermediate said main sections of the mechanism and means for selectively connecting the respective conveyors to the driving means.

14. A sealing mechanism for purposes described, comprising two sealing sections each including a continuous conveyor having spaced pockets to receive containers of the character described, a drive shaft for the conveyor, a container feed hopper, means for receiving containers from the conveyor, and a sealing burner adjacent the conveyor for maintaining flame in contact with exposed end portions of the successive containers to form impervious sealing balls thereon, a drive shaft operatively intermediate the shafts of the respective conveyors, and clutch means for selectively connecting the respective conveyor shafts to the drive shaft.

15. A sealing mechanism for purposes described, comprising a continuous conveyor having spaced pockets adapted to receive containers of the character described, a sealing burner adjacent the path of movement of the exposed container ends, a burner providing a preheating flame anterior to said sealing burner, and means for cooling portions of

the container ends adjacent the zone of pre-heating.

16. A sealing mechanism for purposes described, comprising a continuous conveyor having spaced pockets adapted to receive containers of the character described, a sealing burner adjacent the path of movement of the exposed container ends, a burner providing a preheating flame anterior to said 10 sealing burner, and means for cooling portions of the containers adjacent the zone of preheating and substantially throughout the zone of contact with the sealing flames.

In testimony whereof I have signed this 15 specification this 30th day of December, 1927.

EDWARD E. HENDERSON.
